SACK HOLDER

Filed Jan. 24, 1947

UNITED STATES PATENT OFFICE

2,585,320

SACK HOLDER

Foy F. Hunt, Alhambra, Calif.

Application January 24, 1947, Serial No. 723,916

3 Claims. (Cl. 248—101)

1

My invention relates to the art of packaging, and more particularly to the filling of cloth or paper sacks with comminuted material. The principal use which I have found for it up to this time is in filling sacks with various comminuted food materials, such as grain, chicken feed, or the like, although it may be used to fill sacks with other materials.

The object of the invention is to enable the user to conveniently and quickly fill a sack without danger of tearing the sack.

Further objects and advantages will be made evident hereinafter. The drawing illustrates filling mechanism embodying my invention. In the drawing:

Fig. 1 is a plan view of the mechanism with the spout shown in dotted lines;

Fig. 2 is a section on a vertical plane indicated by the line *a—a* of Fig. 1; and

Fig. 3 is an isometric view showing a portion of my invention, a portion thereof being shown in section.

In the drawing, which illustrates the mode by which I have up to this time contemplated applying my invention, 11 is an inclined spout through which the material to be sacked, for example, grain, is fed by gravity. A closure member (not shown), such as is commonly used on such spouts, is provided, this closure member being operated by a grain control lever 12, which may be grasped by the right hand 13 of the user and which, when pulled upwardly as shown in Fig. 2, allows the grain 14 to flow into a sack 15 held in position as shown in Fig. 2. When the user pushes the lever 12 to its lowermost position, the closure member stops further flow of grain 14 from the spout.

Positioned under the open end of the spout 11 is a frame 21 consisting of legs 22 and horizontal members 23. These members 22 and 23 may be conveniently made of angle iron welded together. Welded to the legs 22 of the frame 21 is a curved, stationary, or primary, bar 24 curved as shown in the drawing. The frame 21 may be tied to the spout 11 by braces 25 and 26. A pair of sliding members 31 and 32 are free to slide within limits toward and away from the user, these members being guided by the horizontal members 23. Welded to the forward end of each of the sliding members 31 and 32 is a movable or secondary bar 33, which is also curved into about the same shape as the primary bar 24. Extending between the members 31 and 32 and welded thereto is a cross bar 34 which has welded

2

to it two ears 35 bored to receive a pin 36. Engaging the pin and pivoted thereon is the forward end of a first rod 41, the other end of which is threaded in a turnbuckle 42, the rod 41 being locked by a lock 43. Threaded in the other or rear end of the turnbuckle 42 is a second rod 44 which may be locked against rotation in the turnbuckle 42 by a lock nut 45. The rod 41 may be secured in the turnbuckle 42 by a right-hand thread, and the rod 44 may be so secured by a left-hand thread. The free end of the rod 44 is provided with a nut 46 and washer 47. The purpose of the turnbuckle is to adjust the distance between the pin 36 and the nut 46. The second rod 44 projects into a casing 51 through a washer 52 threaded in the end of the casing, and a compression spring 53 surrounds the second rod, the spring pressing at one end on the washer 52 and at the other end on the washer 47, tending to force the washers 47 and 52 away from each other. Journaled at 54 on the members 23 is a cross shaft 55 which has rigidly secured to it a pair of toggle cranks 56 carrying a pin 57 which is engaged by an extension 58 of the casing 51. When the sack is being held as hereinafter explained, the pin 57 is above a plane passing through the shaft 55 and the pin 36, forming a toggle which is held in this position, as shown in Fig. 2, by the compression of the spring 53.

Rigidly secured to one end of the cross shaft 55 is an operating crank 61 which carries a pin 62 to which one end 63 of an operating rod 64 is pivoted, the other end 65 of this rod being pivoted to a pin 66. The pin 66 is carried by a bag clamping lever 67 which is pivoted on a pin or bolt 68 carried by the brace 25. The clamping lever 67 and the grain control lever 12 are both so placed as to be readily operated by the right hand 13 of the operator.

The method of using the invention is as follows. The flow of grain being shut off by the closure member in the spout 11, the grain control lever 12 is in its closed position, as shown in dotted lines in Fig. 2. The sack clamping lever 67 is in its released position, and the extension 58 is in the position shown in dotted lines in Fig. 2. The secondary bar 33 is pushed away from the primary bar 24 to the position shown in Fig. 3. The operator, using both hands, pulls the sack 15 up between the bars 33 and 24 so that the bar 33 is inside the sack 15. The operator, using his left hand 71, pulls the sack 15 against the bar 33, the top of the sack tending to overlap the top

of the bar 33, as shown in Fig. 3. The operator can then hold the sack 15 in place, using only his left hand 71, leaving his right hand 13 free to operate the sack clamping lever 67. He pulls this lever forward into the position shown in full lines in Fig. 2, thus pulling the other members into full line position as shown in Fig. 2. This pulls the members 31 and 32 away from him and pulls the bar 33 carrying the sack 15 away from him and clamps the sack 15 solidly between the bars 24 and 33, compressing the spring 53 to insure proper pressure on bags of different thicknesses and insuring that the mechanism, due to the toggle action previously explained, will stay set in closed position after his right hand 13 releases its hold on the sack clamping lever 67. He therefore shifts his right hand to the grain control lever 12 and raises it, thus allowing the grain 14 to flow into the end of the sack held open by his left hand. He allows the grain 14 to flow until the sack 15 is filled with grain. He then pushes the grain control lever 12 down and shuts off the further flow of grain. By then pushing the sack clamping lever 67 away from him, he separates the bars 24 and 33, and the sack is free to drop into a position in which it can be closed and tied.

I claim as my invention:

1. A bag filling mechanism, comprising: a frame; a primary bar fixed to said frame; a secondary bar so guided that it may be moved toward and away from said primary bar; a sack clamping lever; a cross shaft; an operating crank rigidly fixed on said cross shaft; a rod connecting said sack clamping lever to said operating crank; a toggle crank fixed on said cross shaft; a casing having an extension pivoted to the end of said toggle crank; means pivotally connected to said secondary bar and elastically connected to said casing; a pull rod extending into said casing; spring means between said pull rod and said casing; and members through which said pull rod moves said bars toward or away from each other.

2. In a bag filling machine, the combination of: a frame; a primary bar fixed to said frame; a secondary bar having curved ends so shaped

as to fit inside the bag to be filled; members rigidly fixed to said secondary bar and so mounted in said frame that they can slide in said frame in a direction at right angles to the major axis of said bar; a shaft carried by said frame and so mounted thereon that it can turn with relation to said frame; an operating lever by means of which said shaft can be so turned; a bell crank lever rigidly fixed to said shaft; and members so connecting the end of said bell crank lever to said secondary bar that said bar so slides as said shaft is so turned.

3. In a bag filling machine, the combination of: a frame; a primary bar fixed to said frame; a secondary bar having curved ends so shaped as to fit inside the bag to be filled; members rigidly fixed to said secondary bar and so mounted in said frame that they can slide in said frame in a direction at right angles to the major axis of said bar; a shaft carried by said frame and so mounted thereon that it can turn with relation to said frame; an operating lever by means of which said shaft can be turned; a bell crank lever rigidly fixed to said shaft; a compression spring; a member pivoted on said bell crank and so placed as to compress said spring when said shaft is so turned; and a member engaged by the other end of said spring and so connected to said secondary bar that said bar is moved toward said primary bar as said spring is so compressed.
